No. 36,838.

Patented March 8, 1904.

UNITED STATES PATENT OFFICE.

CHARLES J. AHRENFELDT, OF NEW YORK, N. Y.

DESIGN FOR A TEAPOT OR SIMILAR ARTICLE.

SPECIFICATION forming part of Design No. 36,838, dated March 8, 1904.

Application filed February 6, 1904. Serial No. 192,450. Term of patent 7 years.

To all whom it may concern:

Be it known that I, CHARLES J. AHRENFELDT, a citizen of the United States, and a resident of New York city, in the county of New York and State of New York, have invented a certain new, original, and ornamental Design for a Teapot or Similar Article, of which the following is a specification.

In the accompanying drawing the figure is 10 a plan showing the design on the teapot.

What I claim is—

The ornamental design for a teapot or similar article substantially as herein shown.

CHARLES J. AHRENFELDT.
